UNITED STATES PATENT OFFICE.

JOSEPH E. GRANT, OF DETROIT, MICHIGAN.

DESIGN FOR AN ARTICLE OF MANUFACTURE.

45,061.

Specification for Design.

Patented Dec. 23, 1913.

Application filed February 25, 1913. Serial No. 750,698. Term of patent 7 years.

To all whom it may concern:

Be it known that I, JOSEPH E. GRANT, a citizen of the United States of America, residing at Detroit, in the county of Wayne and State of Michigan, have invented a certain new, original, and ornamental Design for an Article of Manufacture, of which the following is a specification, reference being had therein to the accompanying drawing, forming part thereof.

My design may be stamped, printed, im-

printed or otherwise suitably applied to or worked in or upon any suitable material and may be produced on or in, or attached to any desired article of manufacture.

I claim:

The ornamental design for an article of manufacture, as shown and described.

JOSEPH E. GRANT.
